HIS ATTORNEY

UNITED STATES PATENT OFFICE

2,535,792

PLAYHOUSE AND TENT

Harold R. Goodale, Bristol, Conn.

Application June 26, 1948, Serial No. 35,365

10 Claims. (Cl. 135—1)

1

This invention relates to play houses and tents and an object of the invention is to provide improvements in the play tent of my Patent No. 2,153,081. Another object is to provide a combined play tent and play house for a card table or the like. Another object is to provide improved devices for conveniently setting up the tent and supporting it on a table. Another object is to provide a play device wherein a tent is formed below a supporting table and a play house is formed above the table.

To these ends and also to improve generally upon devices of this character, the invention consists in the various matters hereinafter described and claimed. In the drawings,

Fig. 1 is a perspective view.

Fig. 2 is a perspective view of the combined ridge support and play house walls.

Fig. 3 is a perspective view of the device of Fig. 2 in partially folded condition.

In Fig. 1, dotted lines indicate a standard size card table having folding legs 2 and a top 4. The top 4 forms the top of a tent and the floor for a play house. Enveloping the table is a tent of cloth or the like comprising side walls 6 and a roof section 8, preferably of the gable type terminating in a ridge 10. The side walls are suitably decorated to simulate windows and doors or other designs attractive to children. The side walls are joined together at the vertical edges although one corner may be left open to provide for access to the area under the table or one side wall may be cut vertically as at 12 or left unfastened to provide a door.

To increase the play possibilities of the tent and appeal to the housekeeping instincts particularly of girls, the sloping roof of the tent is provided with openings leading to rooms or compartments on the floor of which doll furniture may be placed. Accordingly, one side of the roof is cut out, preferably at two areas leaving a central flap or web 14 and two end flaps or webs 16. The web 14 is supported by triangular walls or partitions 18 and the webs 16 are supported by triangular walls 20, all or some of these being suitably decorated so as to simulate a living room and a kitchen, for instance. The walls or partitions are part of a folding support for the ridge 10. The folding support comprises a rectangular plate or sheet 22 of stiff cardboard or the like which fits vertically between the table top and the ridge 10. It may be creased vertically near the middle as at 24 in Fig. 3 to fold up. Fastened to one side of the sheet 22 as by staples are two cardboard sheets 26 and 28 which

5 carry the triangular walls 18 and 20, the sheets 26 and 28 being suitably decorated to match the connected triangular walls. The latter can fold flat against the sheets 26 and 28 along vertical creases and, when sheet 22 is also folded, a compact package results. The creases in effect are hinge connections.

In setting up the tent, the cloth or equivalent material is laid over the card table to envelop it 10 and make a play tent beneath. The folded support, if not already on the table, can then be inserted through one of the roof openings and unfolded to support both the ridge 10 and the slanting flaps or webs which define the lateral edges of the openings. The openings terminate short of the ridge 10 so that longitudinal flaps or webs 30 will overhang the ridge and hold the ridge securely supported along the top of the sheet 22. The walls of the rooms are shown as 15 decorated with furnishings but in practice it will be understood that there will be great appeal to children to arrange modern and attractive doll furniture on the floor.

I claim:

25 1. In a table supported tent, a tent enclosing sides of the table and having a roof spaced above the table, a vertical supporting wall interposed between the top of the table and the roof, said wall being decorated to simulate the wall of a play room, the roof having an opening exposing the wall and the top of the table, and a portion of the roof beyond the edge of the opening overlapping and resting on the supporting wall.

2. In a table supported tent, a tent enclosing 35 sides of the table and having a roof spaced above the table, a vertical supporting wall interposed between the top of the table and the roof, partitions extending at an angle to the supporting wall, and the roof having an opening terminating short of the partitions to leave roof material supported thereon.

3. In a table supported tent, a tent enclosing 40 sides of the table and having a roof portion provided with sloping sides extending to a ridge, a vertical supporting wall interposed between the table and the ridge, one of the sloping sides having an opening exposing the supporting wall and the table top, and the opening terminating short of the ridge to provide a flap overhanging the supporting wall.

4. In a table supported tent, a tent enclosing 45 sides of the table and having a roof portion provided with sloping sides extending to a ridge, a vertical supporting wall extending the length of 50 the table and interposed between the table and

the ridge, one of the sloping sides having an opening exposing the supporting wall and the table top, the edge of the opening terminating short of the ridge to leave a flap supported on the ridge, and the exposed portion of the supporting wall being decorated to simulate the wall of a room.

5. In a table supported tent, a tent enclosing sides of the table and having a roof portion provided with sloping sides extending to a ridge, a supporting wall interposed between the table and the ridge, a triangular partition extending from the supporting wall and engaging one of the sloping sides to support the latter, and said sloping side having an opening terminating short of the triangular partition.

6. In a table supported tent, a tent enclosing sides of the table and having a roof spaced above the table, a foldable supporting structure interposed between the table top and the roof, said structure comprising a vertical wall and spaced partitions extending in substantial parallelism from one side of the wall and adapted to fold against it, and a portion of the roof having an opening between the partitions to provide for erection of the supporting structure from outside the tent.

7. In a table supported tent, a tent enclosing sides of the table and having a roof portion provided with sloping walls extending to a ridge, a foldable supporting structure interposed between the table top and the roof, said structure comprising a vertical wall extending across the table and engaging the ridge, and triangular partitions adapted to fold against the vertical wall or to extend at right angles thereto, said vertical wall and partitions being decorated to simulate the walls of a room, and one of the sloping walls having an opening between the partitions to expose the decorations and the top of the table.

8. In a table supported tent, a tent enclosing sides of the table and having a roof portion provided with sloping walls extending to a ridge, a

foldable supporting structure interposed between the table top and the roof, said structure comprising a vertical wall extending across the table and engaging the ridge, two pairs of spaced partitions hinged to the vertical wall, and an opening in the sloping roof between each pair of partitions.

9. In a table supported play device, a fabric enclosure having a roof portion over the table and wall portions hanging from the roof portion at the edges of the table, a flat vertical roof-supporting wall interposed between the table top and the roof, said roof having an opening to provide access for setting up said support from outside the enclosure and to provide for insertion of toy furniture onto the top of the table, and the opening terminating short of the roof-supporting wall.

10. In a table supported play device, a fabric enclosure having a roof portion above the table and wall portions hanging from the roof portion at the edge of the table, a foldable support interposed between the table and the roof portion, the roof having an opening to provide for erection of the foldable support from outside the enclosure, at least a portion of the roof beyond an edge of the opening overlapping and resting on the support and the opening being large enough to provide for insertion and arrangement of doll furniture on the floor provided by the table top.
